SPEED CHANGING MECHANISM

John E. Torbert, Jr., National City, Calif.

Original application March 4, 1936, Serial No. 67,146. Divided and this application September 10, 1936, Serial No. 100,183

3 Claims. (Cl. 77—7)

This invention relates to an improved speed changing mechanism particularly adapted for use with electric drill tools and the like and is a division of my co-pending application for a patent 5 for a Drill, Serial No. 67,146, filed March 4, 1936; now Patent No. 2,106,937.

One object of my invention is to provide a speed changing mechanism which will permit the drill chuck of an electric drill or the like to be 10 driven at either high or low speed, depending upon the work to be drilled, so that the necessity of the operator removing his hand from the handle of the device to effect speed changes at remote points will be obviated.

Another object of the invention is to provide a 15 device of this character which will be simple in construction, light in weight, and positive in action.

A further object of the invention is to provide 20 a speed changing mechanism wherein provision is made for turning off or on the motor employed for driving the drive shaft of said mechanism.

A further object of the invention is to provide 25 a speed changing mechanism wherein a removable auxiliary handle is employed for permitting both hands of the operator to be used when it is desired to exert great pressure upon the work being drilled.

Other and incidental objects of the invention 30 will render themselves apparent as the description proceeds.

My improved speed changing mechanism is ill- 35 lustrated in the accompanying drawings, wherein:

Figure 1 is a vertical sectional view of the 35 structure.

Figure 2 is a vertical sectional view of the 40 mechanism, taken along the line 2—2 of Figure 1, looking in the direction indicated by the arrows.

Figure 3 is a transverse sectional view on the 45 line 3—3 of Figure 2.

Figure 4 is a fragmentary detail plan view 50 showing the actuating button shank and opening therefor.

Referring now more particularly to the drawings, wherein like numerals of reference will be 55 seen to designate similar parts throughout the various views, the numeral 1 indicates in general a handle of my improved speed changing mechanism which carries at its upper end a tubular head 2 projecting upwardly and rearwardly therefrom. The handle defines a housing for the gearing employed, as will be seen hereinafter. The rear end of the tubular head is closed by a threaded plug 3. The bore of the head 2 has its

lower portion provided with an opening intermediate its length for permitting the establishment of communication with the handle which is hollow throughout its interior, and in this bore there is fitted a tubular shaft housing 4, held in place and prevented from rotating by set screws 5. Bearings 6 and 7 are rotatably mounted in the shaft housing to support a shaft 8 which terminates at its forward end in a head or nipple 9 formed with a squared shank 10 adapted to correspond to a socket formed in a like shank on a drill chuck which is adapted to be screwed on the projecting threaded end portion 11 of the shaft housing 4. Lock nuts 12, which are adapted to lock the housing 4 in place, are carried by the threaded portion 11. A beveled gear 13 is fixed to the shaft 8 forwardly of the bearing 7 and is adapted to mesh with a companion beveled gear 14 which is carried by a shaft 15 rotatably mounted in the handle 1 by bearing bars 16 and 17 which extend transversely in the handle and are secured in place by screws 18. An opening 19 is formed in the tubular shaft housing 4 in order that the beveled gears 13 and 14 may have ready meshing engagement with each other. By referring to Figure 2 of the drawings, it will be seen that the shaft 15, which is better known as a countershaft, is loosely received in clutch sleeves 20 and 21 which are journaled through the bearing bars 16 and 17, respectively. Disposed on the countershaft 15 and between the clutch sleeves 20 and 21 is a clutch sleeve 22 which is slideable longitudinally on the countershaft but is held against rotation thereon by a key 23. By shifting the clutch sleeve 22 longitudinally upon the countershaft, it will be understood that selective engagement of said clutch sleeve 22 with either of the clutch sleeves 20 or 21 may be had and, furthermore, by disposing the clutch sleeve 22 midway between the clutch sleeves 20 and 21, rotation of the countershaft may be brought to a stop. Actuation of the shiftable clutch sleeve 22 is accomplished through the medium of a boss 24 having arms 25 which are engaged in a circumferentially extending groove 26 formed in said shiftable clutch sleeve. The boss 24 projects from a flat plate 27 which bears against the inner face of a detachable closure plate 28 carried by the handle 1. In order to hold the plate 27 against the closure plate 28 I have provided 50 resilient strips 29 which are carried by blocks 30, which blocks project inwardly from the closure plate 28.

As best seen in Figure 3 of the drawings, teeth 31 project from the resilient strips 29 to engage 55

in grooves 32 formed in the plate 27 and which are adapted to guide sliding movement of said plate. Attention is directed to the fact that when the teeth 31 are out of the grooves 32, as shown 5 in Figure 3, the resilient strips 29 will apply pressure to the plate 27 and hold it firmly against the inner face of the closure plate 28 to prevent the escape of lubricant with which the hollow handle is filled, through an opening 33 formed in 10 said closure plate substantially medially thereof. The opening 33 extends longitudinally of the closure plate and has lateral recesses or extensions 34 and 35, at its opposite ends, which extensions serve as seats for the shank 36 of the actuating 15 button 37. The button 37 terminates in a stem or shank which is tightly screwed into a socket formed in the plate and the shank of the boss 24 and, referring to Figure 4 of the drawings, it will be readily seen that by grasping the button 20 37 the shank 36 thereof may be shifted longitudinally of the opening 33 in either direction for shifting the clutch sleeve 22 from a neutral position, as shown in Figures 1 and 2, to an operative position, in which position it will have operative 25 engagement with the clutch sleeve 20 or the clutch sleeve 21, according to the direction in which the button 37 is moved. When the button reaches either end of the opening 33, it will be moved laterally into either the recess 34 or the 30 recess 35, according to the direction in which it has been shifted, and the shiftable clutch sleeve will thus be firmly held in a set position and rotary motion will be imparted to the shaft 15 either by the clutch sleeve 20 or the clutch sleeve 35 21. The clutch sleeve 20 is formed with a circumferentially extending spur gear 38 which meshes with a companion gear 39 carried by a shaft 40. As best seen in Figure 1 of the drawings, the shaft 40 is journaled through the bearing bars 16 and 17 and has its rear end terminating in a socket 41 adapted to receive the shank 42 of a flexible shaft 43 when the cable 44 of said flexible shaft is screwed into a threaded socket 45 which is formed in the thickened lower 45 end wall 46 of the hollow handle 1. It will be understood that the shaft 40 rotates at the same rate of speed as the flexible shaft 43 and, as the clutch 20 turns at the same rate of speed as the gear 39, rotary motion at a high speed 50 will be transmitted to the shaft 15 and thus to the shaft 8 when the shiftable clutch sleeve is in engagement with the clutch sleeve 20.

The countershaft 15 will be rotated at a reduced speed when the clutch sleeve 22 is in engagement with the clutch sleeve 21, as the clutch sleeve 21 carries, at its rear end, a beveled pinion 47 which meshes with a companion beveled pinion 48 carried by a worm gear 49, the worm gear being rotatably mounted and having the stem 50 thereof journaled in a block 51 which projects rearwardly or downwardly from the bearing bar 17 integral therewith. The marginal teeth of the worm gear 49 are disposed in meshing engagement with threads of the worm 52 65 which is carried on and fixed to rotate with the shaft 40. It will thus be seen that a drill may be operated either at high speed or at low speed, according to the type of material in which an opening is to be drilled. It will further be understood that the actuating button 37 may be quickly 70 shifted for controlling the speed or completely stopping rotation without the necessity of the operator removing his hand from the handle 1 of the tool. A terminal socket 53, to receive the 75 prongs of an electric connecting plug 54, is

mounted in the wall 46 of the handle 1, where it is secured in place by a set screw 55. From the terminal socket 53 extend conductor wires 56 which lead upwardly through the handle 1 and are attached to contacts 57 carried by a block 5 of insulation 58, which is mounted in the inner wall of a socket 59 formed at the rear of a trigger guard 60 which trigger guard projects forwardly from the handle 1 under the head 2. In the guard there is mounted a trigger 61 which is pivoted at its upper end, as shown at 62, and carries a lug 63 for shifting the arm 64 inwardly against the action of a spring for bridging the contacts 57 when pressure is applied to the trigger. 15

It will thus be seen that an operator, grasping the handle 1, may easily pass a finger through the trigger guard and, by applying pressure to the trigger, close a circuit for setting in operation the motor connected to a source of power 20 and to the contacts 57. When the trigger is released, the circuit will be broken by reason of the fact that the spring 65 will urge the arm 64 outwardly out of engagement with the contacts 57.

In some instances, it will be desirable to hold 25 the drill in both hands so that it may be held very easily and so that more pressure may be applied if necessary. Therefore, in order to accomplish this, I provide an auxiliary handle indicated in general by the numeral 66 and which includes 30 a relatively short metal bar 67 having a threaded end portion 68 adapted to be screwed into the socket 69 of a yoke 70. The arms 71 and 72 of the yoke diverge from the socket 69 so that they will have flat contacting engagement with the 35 beveled side faces of a saddle 73 which is formed integral with the head 2 by thickening the intermediate portion of said head. As best seen in Figure 2 of the drawings, this saddle projects from opposite sides of the head to form shoulders 40 and the free or lower end portions of the arms 71 and 72 are bent to form hooks 74 which engage under the shoulders of the saddle. It will also be seen in Figure 2, that when the handle 66 is screwed into the socket 69, the inner end of said 45 handle will engage the upper face of the saddle and will exert a pull upon the arms 71 and 72 of the yoke and cause their hooked ends to be moved into tight binding engagement with the shoulders of the saddle. The handle will thus 50 be firmly held in place on the saddle and the operator may grasp the handle 66 with one hand and the handle 1 with the other hand so that the entire mechanism may be held very easily when in use. 55

When the auxiliary handle is not needed, it is only necessary to rotate the metal bar 67 thereof in a direction to loosen it, so that the hooked ends 74 will be freed from binding engagement with the saddle. The yoke may be shifted longitudinally of the saddle out of engagement therewith so that the auxiliary handle may be laid aside until again needed.

It is thought that a reading of the foregoing description will disclose that I have provided a 65 simple yet highly efficient speed changing mechanism.

Having thus described the invention, what I claim is:

1. In a speed changing mechanism, a handle 70 defining a housing, a head carried by the handle and having a bore, a tubular shaft housing in the bore, a shaft in the housing, a countershaft in the handle, means rotatably mounting the countershaft in said handle, clutch sleeves rotatably 75

mounted on said countershaft, a movable clutch sleeve slidable on the countershaft and fixed to rotate therewith, means carried by the handle for shifting the movable clutch sleeve, a drive shaft carried by the handle, a flexible shaft operatively connected with the drive shaft, a worm carried by the drive shaft near its lower end, a gear carried by the shaft at its upper end, a gear carried by one of the clutch sleeves and adapted to engage said first mentioned gear, means rotatably connecting the worm with the other of said clutch sleeves, and means for imparting rotation from the countershaft to the first mentioned shaft, said movable clutch sleeve being adapted for connecting the countershaft to one of said clutch sleeves for relatively slow rotative movement or to the other of said clutch sleeves for relatively fast rotative movement.

2. In a speed changing mechanism, a handle defining a housing, a head carried thereby and having a saddle, an auxiliary handle associated with the head and having a relatively short bar terminating in a threaded end portion, and a yoke having arms straddling the saddle and terminating in hooks adapted to engage the saddle, said short bar being adapted to be screwed into the yoke for tightening the hooks against the saddle and retaining the auxiliary handle on the head and said bar being rotatable for releasing the auxiliary handle from the head.

3. In a speed changing mechanism, a handle defining a housing, a head formed thereon and having a bore, a shaft housing carried by the bore, a shaft rotatable in the bore, bearings journaling the shaft in the bore, a countershaft carried by the handle, beveled gears for transmitting rotation from the countershaft to said first mentioned shaft, clutch sleeves rotatably mounted on the countershaft and having gears thereon, a movable clutch sleeve slidable longitudinally on the countershaft and fixed to rotate therewith, means carried by the handle for shifting the movable clutch sleeve, a drive shaft, a flexible shaft exteriorly of the handle and operatively connected with the drive shaft, a gear carried by the drive shaft and adapted to mesh with a gear of one of the clutch sleeves for transmitting high speed rotation to said clutch member, a worm carried by said drive shaft for transmitting low speed rotation to the other of said clutch sleeves, and bearing bars carried within the handle for mounting said shafts and sleeves, said movable clutch sleeve in one position being adapted to transmit relatively slow rotative movement to the first mentioned shaft and in another position to transmit relatively high speed rotative movement to said first mentioned shaft and said movable clutch sleeve being shiftable to an intermediate position for retaining the countershaft in a non-rotating position.

JOHN E. TORBERT, JR.
